UNITED STATES PATENT OFFICE.

JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

FEEDING MECHANISM FOR SEWING MACHINES.

Original application filed June 28, 1921, Serial No. 481,032. Divided and this application filed October 9, 1923. Serial No. 667,453.

To all whom it may concern:

Be it known that I, JOHN P. WEIS, a citizen of the United States, residing at Nyack, in the county of Rockland and State of New York, have invented certain new and useful Improvements in Feeding Mechanism for Sewing Machines, of which the following is a specification.

This invention relates to sewing machines, and more particularly to that type or style of machine having a horn, which in the present instance is preferably of cylindrical construction wherein the feeding and part of the stitching mechanisms are contained and operated for the purpose of working upon or forming tubular goods, an object of the invention being to provide a sewing machine adapted to operate efficiently at high speeds and comprising improved feeding mechanism coacting with the presser foot for feeding the work through the machine.

This application is a division of my co-pending application for sewing machines filed June 28, 1921, Serial No. 481,032, and a further object of the present invention is to provide a feeding mechanism for sewing machines embodying improved adjusting means, preferably self-locking, for regulating the length of stitch or the throw of the feed dog. In the present instance the length of stitch of the throw of the feed dog is regulated by means of an adjusting instrument, and is self-locking so as to prevent unauthorized persons from changing the length of stitch, or otherwise tampering therewith.

Other objects of this invention will appear in the following description and appended claims, reference being had to the accompanying drawings forming a part of this specification, wherein like reference characters indicate corresponding parts in the several views and wherein Fig. 1 is a side elevation of the machine illustrating particularly the transmitter or driving mechanism, which is shown in operating position beneath the machine but detached from the work table to more clearly illustrate the relation of the transmitter with the sewing machine; Fig. 2 is a rear elevation of the machine, illustrating the connections for the needle drive and a portion of the looper and feed actuating mechanisms; Fig. 3 is a top

plan view of the feeding mechanism, the overhanging arm and cylinder of the machine being shown in broken lines; Fig. 4 is a sectional view taken on lines 4-4 of Fig. 6; Fig. 5 is a sectional detail view taken on line 5-5 of Fig. 6, and illustrates a portion of the feed bar with the eccentric bushing, lock nut and screw which comprise means for raising and lowering the feed; Fig. 6 is a side elevation of the feeding mechanism, partly in section, and illustrating the overhanging arm and the machine frame in broken lines; Fig. 7 is a vertical sectional view of the crank shaft and bearings thereof illustrating the manner in which the parts are lubricated from the overhead reservoir and the tubular outlets leading to the several bearings, also showing in elevation the oil pump, oil pump driving wheel, and the tubes conducting the oil from the oil pump to the reservoir at the top of the machine; and Fig. 8 is a side elevation of the mechanism shown in Fig. 7, also illustrating the construction of the machine frame together with parts of the lubricating mechanism.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

Referring to the drawings it will be seen that the present machine is mounted upon a suitable table 1 and comprises a machine frame of special oil-tight construction having flanges 2 and 3 for supporting and securing the machine to the table. The main portion of the frame is preferably of hollow rectangular construction, closed at the bottom, and having a front wall 4 and a rear wall 5 provided with an opening 6 adapted to be closed by means of a cover plate 7 attached thereto in any suitable manner. This cover plate is provided with a hollow projecting portion 8 within which operates a stop lever for the stopping and starting mechanism of the machine. The outline or shape of the opening 6 is irregular in form and is indicated at 6^a, 6^b, 6^c, 6^d,

6°, and 6°, the cover plate 7 being of similar form and adapted when closed to seal the opening against leakage of oil. The front wall 4 of the frame is provided with a boss 11 bored to receive a cylinder 12. The side wall 13 of the frame is provided with a boss 14 for receiving one of the crank shaft bushings 15, the opposite side wall having a boss 100 for receiving the opposite crank shaft bushing 99. The frame is provided with inwardly projecting bosses 26 and 29 bored to receive bushings for supporting the crank shaft of the machine. Projecting from the front wall 4 is an overhanging arm 15 32 terminating in a bearing 33. A presser bar 183 reciprocates vertically in a bushing 187 carried by the bearing 33, and a presser foot 188 is secured to the lower end of the presser bar. Above this bearing is a rectangular opening 34 through which the presser foot lifting member 180 operates. A needle bar 48 operates in the bearing member 33 and is provided with suitable needle mechanism 51, the needle bar being operated by suitable mechanism described in my above mentioned application.

As shown in Fig. 8, the rear wall 5 is inclined to the left of the perpendicular, an advantage thereof being to assist in properly 30 conducting the lubricant from one interior part to another and to finally conduct it into the reservoir formed by the bottom 9 and side walls 4, 5, 13 and 16 of the frame. To empty the reservoir, drain pipe 10 is 35 tapped into the bottom 9. The side wall 16 has a rectangular opening 24 into which projects a laterally extending portion of the stop lever 118, this opening also affording a passage for the lubricant returning 40 from the bushing of the crank shaft housed in the boss 100. The side wall 16 around the rectangular opening 24 is provided with a suitable boss forming a seat for a belt guard 22 which covers the drive belt 23, 45 and the clutch and pump wheels 93 and 425.

Mounted in end bearings 15 and 99 of the frame, and in suitable bearings in bosses 26 and 29 is a transversely extending crank shaft 63 having a clutch wheel 93 provided 50 with a suitable belt groove over which passes belt 23 of the transmitter.

The power transmitter comprises in general a main bracket 143 secured to the bottom of the table in any suitable manner, the bracket having an arm bored to receive a shaft 144. Upon this shaft is mounted a cone pulley 145 over which operates a belt 146 for transmitting power from any suitable line shaft to the pulley. The belt 23 is 55 driven by a pulley 149 for operating the sewing machine. Suitable clutch mechanism for the pulleys 145 and 149 is provided which is controlled by means of a rod 156 connected to a floor treadle (not shown). A further 60 detailed description of the power transmitter

mechanism is not deemed necessary herein since the same is fully described in my co-pending application.

Referring particularly to Figs. 3, 4, 5, and 6 a four motion feeding mechanism co-acting with the presser foot is provided for feeding the work through the machine. This feeding mechanism embodies self locking adjusting means for regulating the length of stitch or the throw of the feed dog, such regulation being accomplished by an adjusting instrument, preferably as herein shown in the form of a keywrench, thereby to prevent unauthorized persons from changing the length of stitch. Such adjusting means may preferably be so constructed as to be manipulated only by a special instrument, thus rendering it a simple matter to change the length of stitch merely by turning the adjusting means one way or the other to the desired position, as indicated by a gauge registering the length of stitch required.

The feed mechanism comprises a feed dog 208 which may be of any preferred form to suit the character of work. The shank 209 of the feed dog is slotted at 210 to receive a forward attaching screw 217, and also has an open ended slot 211 to receive the rear attaching screw 218. The attaching screws are tapped into the forward end 212 of the feed bar generally indicated at 213. The bottom surface of the feed dog is cut away at an angle at each side of the center line 214, to give free space at 215 and 216 to permit the feed dog to be tilted so that the toe of the feed dog will engage the work in advance of the heel, or vice versa, or to permit the feed to be leveled. These adjustments are obtained by adjusting the attaching screws as desired, as for instance, if the screw 217 is loosened and the screw 218 is tightened, the toe of the feed will be tilted upward. If this adjustment is reversed the toe will be tilted downward, and the heel will engage the work first.

By virtue of such adjustment the work may either be gathered or stretched, or fed out smoothly without either gathering or stretching. Furthermore after a predetermined adjustment of the feed has been made, the feed may be removed at any time without destroying or disturbing such adjustment by merely removing the forward screw 217 without disturbing the rear screw 218, and withdrawing the feed dog 208 from the machine. The same may thereafter be replaced and at the same time maintaining such predetermined adjustment, because the rear open slot 211 of the feed dog permits the removal thereof without disturbing the screw 218.

The feed bar 213 is rockably supported in the cylinder 12 by a swinging yoke link 220

embracing the bar and supported by a stud screw 219. The yoke is connected to the feed bar 213 by a bolt 221 having a shoulder 222 operating in one side of the link, while a nut 223 having a shoulder 224 operates in the opposite side of the link 220.

The feed bar is bored to receive an eccentric bushing 225, which is clamped between the inside faces of the yoke link by the bolt 221 and nut 223. The shoulder 224 of this nut is tapped to receive the thread portion 226 of the bolt, while the body 228 of the bolt fits freely into the eccentric bushing. The shoulder 222 of the bolt and the shoul-

der 224 of the nut 223 clamp the bushing securely to the bolt and to the side walls of the link 220, permitting the feed bar 213 to rock on the eccentric bushing. It will be seen that the construction is such that the height of the feed dog may be adjusted relative to the throat plate merely by turning the eccentric 225. The cylinder 12 is provided with an aperture 229 in each side wall through which may be inserted screw drivers to engage the heads of the bolt 221 and the nut 223, and by loosening the nut and turning the bolt the eccentric will be turned with it so as to raise or lower the feed dog to the desired height. The ad-

justment is locked by holding the bolt with one screw driver and tightening the nut with another. Four-motion movements are transmitted to the feed bar by the ball crank 69 of the crank shaft operating in the bearing 230 of the feed lever 231. The rear end 232 of the feed bar 213 is connected to the feed lever 231 by means of a joint pin 233 secured in the feed lever 231. The feed lever has a

plate 234 secured thereto which forms one wall of a slideway in which operates a slide block 235. This slide block is supported by and slides on a stud screw 236 carried by arms 237 and 238 of an adjusting yoke 239 adjustably mounted on a vertical post 240 secured in the machine frame at 241 and 242. The post 240 is preferably tubular and the lower end is provided with a flattened guide piece 243 secured in the tube by a pin 244, and projecting downwardly into a slot

245 of the rear end 232 of the feed bar and preventing lateral movement thereof. The forward end of the feed bar 213 is guided against lateral movement by the side walls 246 of the slot 247 formed in the end bearing 248.

The adjusting yoke 239 is slotted at 249 to receive a key nut 250 provided with a flange 251 secured to the yoke by screws 252. The inner portion of the key nut is screw threaded to engage the left hand threads 254 on the lower end of a vertical screw 255, the upper end of which is provided with right hand threads 256 engaging corresponding threads in the post as at 257. The upper end of the screw 255 is provided with a

flattened key 258 to receive a key wrench 260 for turning the screw, the upper end of the post being bored at 259 to receive the wrench, and also bored to a larger diameter than the screw below the threaded portion 257.

In operation therefore in order to adjust the length of stitch or throw of the feed dog, it is merely necessary to insert the key wrench 260 into the post until the notch 261 engages the key 258 and then turn the screw in the desired direction either to shift the adjusting yoke 239 up or down on the post, thereby lengthening or shortening the throw of the feed dog. Turning the screw to shift the yoke 239 and slide block 235 upward increases the amplitude of movement of the feed lever 231 thereby imparting increased movement to the feed bar 213 and to the feed dog 208. Adjustment in the opposite direction decreases the longitudinal move-

ment of the feed dog due to the fact that as the slide block 235 is moved downwardly in the guideway an increasingly restricted lateral movement is imparted to the feed bar 213 by the feed lever 231 operating on the adjustable fulcrum formed by the rocking slide block 235. An adjustable collar 262 is mounted on the post 255 above the yoke 239 to limit the upward movement of the yoke when adjusted at the proper point. The machine casting is provided with a projecting portion 263 against which the yoke may engage, thereby limiting the downward movement thereof. From this construction therefore it will be seen that the necessity of any locking device for locking the adjusting means in adjusted position is obviated as the adjustment cannot change of itself. The stops 262 and 263 limit the feed dog movement in order to prevent it from striking either end of the feed slots in the throat plate. The key wrench 260 is provided with a scale of graduations 260^a representing or indicating predetermined lengths of stitches or movements of feed, and such graduations register with an indicator 264 which aligns with the body of the key wrench when it is in position for adjusting the feed. Thus the key wrench and cooperating parts constitute not only a means of accurate and minute adjustment of the length of stitch or movement of feed but also a micrometer gauge for measuring accurately to fractions of an inch the length of stitch at any time.

It is merely necessary to insert the key wrench in position and the indicator will point to the proper graduation representing the exact length of stitch.

From the foregoing it will be seen that the length of stitch can be changed while the machine is in operation, and that by means of the right and left hand threads on adjusting screw 255 the latter will after each adjustment be effectually locked against dis-

turbance and can not turn of itself on account of the vibration of the machine. This screw 255 is therefore self-locking and can be turned only by inserting the key wrench 5 through the opening at the top of the tube or post 240. It will be noted that by virtue of the engagement of the upper set of threads of the screw with threads 257 at the upper end of tube 240 the screw when 10 rotated will shift endwise. Thus if the pitch of the thread on the screw is $\frac{3}{16}$ inch the fulcrum will be shifted $\frac{1}{16}$ inch upon each rotation of the screw.

The hollow rectangular frame of the machine forms a fluid-tight oil chamber within 15 which is located mechanism driven from the crank shaft for automatically lubricating the various operating parts, as described in my above mentioned co-pending application. 20 It will be particularly noted that the entire mechanism for adjusting the length of stitch is housed within this compartment or hollow frame, as shown in Fig. 6, and that there are no openings in the frame through 25 which lubricant can escape.

This is highly important in a machine that is automatically lubricated since the oil will escape through any opening at the sides or top of the oil chamber. This fulcrum 30 adjusting mechanism is entirely encased within the rectangular frame out of sight, and nothing appears on the outside of the machine to suggest such an adjustment. This is also important because the type of 35 machine in which it is used requires that the stitch be changed only by an authorized person such as the foreman, and not by the operator.

From the foregoing construction of the 40 machine frame it will be noted that this frame forms a reservoir having the four sides and the bottom integral, and when the rear cover plate 7 and the belt guard 22 are applied, the entire structure is closed and is 45 sealed against any possible leakage of oil. It is further to be noted that the feed mechanism, the adjusting mechanism therefor, and the locking mechanism are housed within the machine frame, and at the same time, 50 the construction is such that the adjustment of the feed mechanism may be obtained not only during the operation of the machine, but without permitting the leakage of oil.

As hereinbefore stated, the machine frame 55 forms an oil reservoir, and automatic lubricating mechanism is provided for the various bearings of the machine. Adjacent to the bottom 9 of the frame and located in the side wall 16 is an inwardly projecting boss 60 30 bored to receive a pump casing 31, (see Figs. 7 and 8). A pump belt wheel 425 is carried by a shaft 426 at the end of which is attached a small gear 427 meshing with a similar gear 428 carried by a shaft 429.

65 These gears operate in a suitable recess of

the pump casing 31, and the casing is provided with a peripheral groove filled with wicking 431 for making a leak-proof fit between the casing and the hole into which it fits. A cover plate 432 is secured at 70 433 to the pump casing thereby covering the gears, and the casing is made air tight by means of packing 434.

The plate 432 is provided with an inlet 75 for the lubricant which is drawn in by the gears and forced up thru a pipe 435 to a reservoir 439 provided with a top cover plate 447. The oil is delivered from the reservoir 439 through outlet tubes 451, 452, 453, and 454, each of which having its delivering end 80 located to deliver oil therefrom to the respective bearings. The tube 454 conducts oil to the funnel 455 carried by a horizontal tube 456, the end 457 directing lubricant to the bushing 15, and the opposite end 458 directing lubricant to the bushing 101^a. The tube 451 supplies the intermediate bearings of the crank shaft 63. The tube 452 supplies the crank 67 and other mechanism such as the looper actuating mechanism. The tube 453 supplies the crank 69 and the feeding mechanism with lubricant. Portions of the lubricant thrown from the cranks 67 and 69 are caught by the plate 459 secured to the cover plate 7 which has a tapered extension terminating in a spout end 461, for delivering oil directly to the reservoir 125 of the stop lever 118, this supplying the oil buffer 124 of the stop lever. The oil buffer is connected with the reservoir 125 by holes 124^a. The lubricant is directed through the crank shaft, and the escaping lubricant is caught in a separate receptacle 469, thence passing through the outlet 470 into the interior of the machine.

Some of the oil which escapes to the belt 100 wheel 93 is thrown off from this wheel and caught inside the belt wheel guard 22 by receptacles 469 and 472, the latter receptacle 105 having an outlet 473 into the interior reservoir of the machine frame. It is noted that the outlet tubes 470 and 473 project through the rectangular opening 24 in the side wall of the machine frame. The pump is operated by means of a pulley wheel 425 which 110 is operated from the drive belt 23.

A further detailed description of the lubricating mechanism is not herein deemed necessary since the same is fully described in my co-pending application, Serial No. 678, 115 398, filed December 4, 1923, it being noted however that the various mechanisms of the machine are automatically lubricated, that the machine frame forms of itself an oil reservoir, and that this machine frame contains various operating parts including the feeding mechanism and the adjusting mechanism therefor. Furthermore, the construction of the machine frame is such that it is 120 oil tight and yet permits the adjustment of 125 130

the feed mechanism from the outside without leakage of oil, and without stopping the operation of the machine.

- It is to be understood that by describing in detail herein any particular form, structure or arrangement, it is not intended to limit the invention beyond the terms of the several claims or the requirements of the prior art.
- 10 Having thus explained the nature of my said invention and described a way of constructing and using the same, although without attempting to set forth all of the forms in which it may be made, or all of the modes 15 of its use, I claim:

1. In a sewing machine, the combination of a four-motion feed bar, a feed dog pivoted to said feed bar, and a pair of vertical adjusting screws extending thru said feed dog 20 at opposite sides of said pivot and cooperating with the feed bar for swinging said feed dog relatively to said feed bar.

2. In a sewing machine, the combination of a four-motion feed bar, a feed dog pivoted to said feed bar, and a pair of vertical adjusting screws extending thru said feed dog 25 at opposite sides of said pivot and cooperating with the feed bar for swinging said feed dog relatively to said feed bar, said feed dog

30 having a horizontal open slot for receiving one of said screws to permit removal of the feed dog without disturbing the adjustment of said screw.

3. In a sewing machine, the combination 35 of a reciprocating feed bar having an upper horizontal face, a feed dog having oppositely inclined bottom faces resting upon said horizontal face, and a pair of adjustable devices shiftable in opposite directions for adjustably tilting said feed dog on said horizontal face.

4. In a sewing machine, the combination 45 of a reciprocating feed bar having an upper horizontal face, a feed dog having oppositely inclined bottom faces resting upon said horizontal face, a pair of adjustable devices shiftable in opposite directions for adjustably tilting said feed dog on said horizontal face, and means for permitting removal of said feed dog without disturbing the adjustment 50 of one of said devices.

5. In a sewing machine, the combination 55 of a feed bar having a horizontally extending feed dog supporting portion, a feed dog having a horizontally extending shank overlapping said portion and pivoted thereon, a pair of vertical adjusting screws extending thru said shank and cooperating with the feed bar, said shank having at its rear end an open slot adapted to receive one of said screws and to permit removal of the feed dog without removing said last screw.

6. In a machine, the combination of a 60 four-motion feed bar, a feed dog having the base thereof provided with a pair of oppo-

sitely inclined faces, and a pair of independently shiftable means extending through said faces for adjustably connecting the feed dog to the feed bar.

7. In a sewing machine, the combination 70 of a feed bar, means for operating the same, a feed dog supported on said bar, said dog having the bottom thereof formed with oppositely inclined faces adapted to bear against the upper face of said bar, and means intermediate the ends of each inclined face for adjustably connecting said feed dog to the feed bar.

8. In a sewing machine, the combination 80 of a drive shaft, feeding mechanism connected thereto and comprising a feed bar, swinging means for supporting the same, a feed dog carried by said feed bar, and means carried by said swinging means for raising or lowering said feed bar relatively to said 85 swinging means.

9. In a sewing machine, the combination 90 of a drive shaft, feeding mechanism connected thereto and comprising a feed bar, a feed dog carried thereby, swinging supporting means for said feed bar, means for varying the height of said feed dog and comprising an adjustable eccentric carried by said supporting means.

10. In a sewing machine, the combination 95 of a drive shaft, a vertically extending member pivoted at its lower end for swinging movement, an adjustable eccentric carried at the upper end of said member, and a feed bar 100 operated from said shaft and supported on said member through the medium of said eccentric.

11. In a sewing machine, the combination 105 of feeding mechanism comprising a feed bar and a feed dog carried thereby, means for swingingly supporting such feed bar, a rotatable eccentric carried by said means and cooperating with the feed bar for adjusting the feed bar relatively to said means.

12. In a sewing machine, the combination 110 of an upright supporting yoke pivoted at its lower end for swinging movement, a rotatable eccentric carried at the upper end of said yoke, and a feed bar supported on said yoke through the medium of said eccentric.

13. In a sewing machine, the combination 115 of a work support, a feed bar, a feed dog connected thereto, means for imparting a four-motion path of movement to said feed bar, a swinging member pivotally supported by said work support, means carried by said member for adjusting the height of the feed bar relatively to said member to vary the path of movement of the feed dog.

14. In a sewing machine, the combination 120 of a drive shaft, feeding mechanism controlled thereby and comprising a feed bar, a feed dog carried by said feed bar and means for adjusting the throw of said feed bar, said last means comprising an endwise shiftable 125

adjusting screw having two sets of threads, one set operative in cooperation with a stationary threaded portion of the machine for maintaining the same against displacement during the operation of said drive shaft, and the other set operative to effect said adjustment.

15. In a sewing machine, the combination of a machine frame, a drive shaft supported thereby, a feed lever eccentrically connected thereto, cloth feeding means connected to said lever, a vertically shiftable fulcrum member forming an adjustable fulcrum for said feed lever, a vertical tubular member mounted in said frame, a screw housed within said member and having at its upper end a key located below the top of said tubular member, said tubular member having a vertical slot at its lower end, a key nut secured to said fulcrum member and extending into said slot and having threads engaging a set of threads on said screw, said screw having a set of threads at its upper end engaging threads in said tubular member, one of said sets of threads being left hand and the other set right hand threads, and a key wrench adapted to be inserted into said tubular member for rotating said screw.

30 16. In a sewing machine, the combination of a machine frame, a shaft supported thereby, a feed lever eccentrically connected to the shaft, cloth feeding means connected to said lever, a vertically adjustable fulcrum member for said feed lever, a vertical tubular member mounted in said frame, a screw held within said member and having at its upper end a key located below the top of said tubular member and having at its lower end threads effective upon operating said screw for adjusting the fulcrum, and means coacting with said key for operating the screw.

35

40

45 17. In a sewing machine, the combination
of a machine frame, a shaft supported there-
by, a feed lever eccentrically connected to
the shaft, cloth feeding means connected to
said lever, a vertically adjustable fulcrum
member for said feed lever, a vertical tubu-
50 lar member mounted in said frame, a screw
held within said member and having at its
upper end a key located below the top of
said tubular member and having at its lower
end a set of threads, said tubular member
having a vertical slot and said fulcrum hav-
55 ing a threaded portion extending through
said slot and engaging said set of threads,
and means insertable into said tubular mem-
ber and co-acting with said key for operat-
60 ing said screw.

18. In a sewing machine, the combination of a machine frame, a shaft supported thereby, a feed lever eccentrically connected to the shaft, cloth feeding means connected to said lever, a vertically adjustable fulcrum

member for said feed lever, a vertical tubular member 65 mounted in said frame, a screw held within said member and having at its upper end a key located below the top of said tubular member and having at its lower end a set of threads, said tubular member 70 having a vertical slot and said fulcrum having a threaded portion extending through said slot and engaging said set of threads, said screw having at its upper end a set 75 of threads engaging interior threads carried by said tubular member.

19. In a sewing machine, the combination of a machine frame, a shaft supported thereby, a vertical reciprocating feed lever connected to said shaft, a feed bar operated by said feed lever, an adjustable fulcrum member for said feed lever, a vertical screw connected to said fulcrum member for adjusting the same, a vertical tubular post carried by said machine frame for housing said screw, said post having adjacent the upper end thereof a set of interior threads engaging exterior threads on such screw. 80 85

20. In a sewing machine, the combination of a drive shaft, a feed lever eccentrically connected thereto, and adjustable fulcrum member connected to said feed lever, a vertical screw having a set of threads for shifting said fulcrum member and a set of threads co-acting with fixed means carried by the machine, one set of threads being right hand and the other set left hand threads, and means for rotating said screw to vary the throw of the feed lever. 90 98

21. In a sewing machine, the combination of a drive shaft, a feed lever operated thereby, adjustable slide means forming a fulcrum for said lever, a vertical screw having two separate sets of threads, one set co-acting with threads carried by said slide means and the other set co-acting with a stationary threaded portion carried by the machine, and means for rotating said screw to adjust said slide means.

22. In a sewing machine, the combination of a machine frame, a drive shaft carried by the frame, a feed lever connected to said shaft, a feed bar connected to said feed lever, an adjustable slide means forming a fulcrum for said feed lever, a vertical screw for shifting said slide means and entirely housed within a vertical tubular portion carried by the frame, the upper end of said screw being located within and a substantial distance below the top of said tubular portion, and an implement adapted to be inserted through the top of said tubular portion for operating the screw. 110 115 120

23. In a sewing machine, the combination of a drive shaft, feed mechanism controlled thereby and comprising a feed bar, means for regulating the throw of said feed bar and including an adjusting screw having two 125

sets of oppositely inclined threads effective to maintain the screw against displacement during the operation of the machine.

24. In a sewing machine, the combination 5 of a rotary shaft, a feed bar, a feed lever connected to said feed bar and shaft, an adjustable fulcrum for said feed lever for varying the effective movement of said feed bar, and a screw having a set of threads, for 10 adjusting the fulcrum and a set of oppositely inclined threads coacting with a stationary part of the machine.

25. In a sewing machine, the combination 15 of a drive shaft, feed mechanism controlled thereby and comprising a feed bar, means capable of operation while the machine is in operation for regulating the throw of the feed bar and including a rotary adjusting screw having means for preventing dis- 20 placement of the screw during the operation of the machine.

26. In a sewing machine, the combination 25 of a hollow machine frame having an oil tight oil carrying chamber, a drive shaft, lubricating mechanism automatically operated from said shaft, feed mechanism including a feed bar, means extending into said chamber for regulating the throw of said feed bar, means for operating said means from the 30 outside of the machine while the machine is in operation, and means for forming an oil tight joint about said first means.

27. In a sewing machine, the combination 35 of a hollow machine frame having an oil tight oil carrying chamber, a drive shaft, lubricating mechanism automatically operated from said shaft, feed mechanism including a feed bar, means extending into said chamber for regulating the throw of said feed 40 bar and having two sets of oppositely inclined threads, means for operating said means from the outside of the machine while the machine is in operation, and means for preventing the escape of oil past said first 45 means.

28. In a sewing machine, the combination 50 of a drive shaft, a feed bar, a feed dog carried by said feed bar, a reciprocating feed lever connected to said shaft and feed bar, and means for adjusting the throw of said feed bar and comprising a rotary member having two sets of differently inclined threads effective to maintain said member against displacement.

55. 29. In a sewing machine, the combination of a drive shaft, a feed bar, a feed dog carried by said feed bar, a reciprocating feed lever connected to said shaft and feed bar, and means for adjusting the height and length of feed, said means comprising a swinging supported rotatable eccentric cooperating with the feed bar and a shiftable fulcrum cooperating with the feed lever.

30. In a sewing machine, the combination

of a drive shaft, a feed bar, a feed dog carried by said feed bar, a reciprocating feed lever connected to said shaft and feed bar, and means for adjusting the height and length of feed, said means comprising an eccentric pivot carried by the feed bar, a movable fulcrum carried by said feed lever, and a threaded member for shifting said fulcrum, said member having reverse threads for maintaining itself against displacement.

31. In a sewing machine, the combination 65 of a hollow machine frame forming an oil tight chamber carrying an oil bath, a drive shaft, feed actuating mechanism connected to said shaft and extending into said oil chamber, means extending into said oil chamber for adjusting said feed actuating mechanism, and means for operating said last means from the outside of said oil chamber during the operation of the machine and 75 without the escape of oil therefrom.

32. In a sewing machine having a drive shaft and lubricating mechanism automatically operated therefrom, the combination 80 of a hollow machine frame enclosed against the escape of oil therefrom and forming an oil tight oil carrying reservoir, a feed lever connected to said shaft, a feed bar connected to said lever, means located entirely within said frame for regulating the length 85 of stitch and including an adjustable fulcrum for said feed lever, and means operable from the outside of said machine frame for operating said means.

33. In a sewing machine, the combination 90 of a machine frame, a drive shaft carried thereby, a feed bar, means comprising a feed lever for operating said feed bar from said shaft, an adjustable fulcrum cooperating with said feed lever means for adjusting the same comprising a slide member and an adjusting screw co-acting therewith, said screw being housed within the machine frame against access, and a removable implement capable of operating said screw 95 while the machine is in operation, said implement and machine frame having one a scale indicating the length of pitch and the other an indicator cooperating with said scale.

34. A sewing machine having lubricating mechanism, and comprising a hollow frame forming an oil tight oil carrying chamber for said lubricating mechanism, a shaft extending into said oil chamber and operating said mechanism, a feed lever connected to said shaft, a feed bar connected to said lever, and means extending into said oil chamber for regulating the feed and including an adjustable fulcrum for said feed lever.

35. A sewing machine having lubricating mechanism, and comprising an oil tight hollow machine frame having an oil chamber

for said lubricating mechanism, a drive shaft carried by said frame and operating said mechanism, feed mechanism, means within said frame for operating said feed mechanism from the drive shaft, means cooperating with said last means for regulating the feed and extending into said oil chamber, and means capable of controlling said last means during the operation of the feed mechanism and lubricating mechanism.

36. A sewing machine having lubricating mechanism, and comprising an oil tight hollow machine frame having an oil chamber for housing said mechanism, a drive shaft carried by said frame for automatically operating said mechanism, feed mechanism, means for operating said feed mechanism from the drive shaft, means cooperating with said last means for regulating the feed and extending into said oil chamber, and detachable means accessible from the outside of the machine frame and capable of controlling said last means during the operation of the feed mechanism and lubricating mechanism.

37. In a sewing machine, the combination of a machine frame, a shaft carried thereby, a feed bar, a reciprocating lever connected to the said shaft for operating the feed bar, said machine frame having a vertical tubular portion having an opening at the top thereof, a rotary screw housed in said tubular portion with the upper end of the screw normally located a substantial distance below the top of said tubular portion, and an implement having a part adapted to be inserted through the top of said tubular portion to co-act with the screw for rotating the same, said frame and implement having one

a scale and the other an indicator for determining the length of stitch.

38. A sewing machine having lubricating mechanism and comprising a machine frame having an oil tight oil chamber, a drive shaft for operating said mechanism, feed mechanism operated from said shaft, means normally inaccessible from the outside of the machine and extending into said oil chamber for regulating the feed, and means for preventing the escape of oil from the oil chamber past said means during the operation of said lubricating mechanism.

39. A sewing machine having lubricating mechanism and comprising a machine frame having an oil tight chamber, a drive shaft for operating said mechanism, feed mechanism operated from said shaft, means extending into said oil chamber for regulating the feed, means for operating said means from the outside of the machine, and means for preventing the escape of oil from the chamber past said first means.

40. A sewing machine having lubricating mechanism and comprising a hollow machine frame having an oil chamber, a drive shaft operating said lubricating mechanism, a feed bar, a feed lever connected to said feed bar and operated from the shaft, a fulcrum slide cooperating with said lever, and adjusting screw extending into said oil chamber for shifting said fulcrum slide, means for housing said screw against the escape of oil from said chamber, and means for operating said screw from the outside of the machine frame.

Signed at Nyack, New York, this 8th day of October, 1923.

JOHN P. WEIS.
